UNITED STATES PATENT OFFICE

JOSE MIERES, OF BUENOS AIRES, ARGENTINA

GARTER

Application filed August 20, 1931. Serial No. 558,279.

This invention relates to garters and the like, and particularly to garment supporting means of garter type.

The main objects of this invention are to provide an improved form of garter for supporting garments, such as socks, stockings, gloves and the like; and to provide an improved arrangement of garter fastening means which will permit the garter to be concealed by the garment to be supported.

An illustrative embodiment of this invention is shown in the accompanying drawing, in which:

Figure 1 is a perspective view of a complete garter showing the clasp or garment holding means in open or inoperative position.

Fig. 2 shows front and side details of the clasp.

In the form shown, the improved garter comprises a strip 1 of elastic material such as rubber, adapted to encircle the limb of the wearer. The inner surface of the strip 1 is made up of a flat surface, pitted with closely spaced depressions 2, which have the effect of cuppings to retain the garter in position upon the limb. The depressions enable the strip to adhere to the skin without causing discomfort to the wearer, since the pressure required to make proper contact with the skin is very slight.

The strip 1 is also provided with a plurality of apertures 3 adjacent its marginal edges.

Buttons 4 are inserted in two of the apertures 3 at one of the remote ends of the strip 1 and are adapted to engage two of the apertures in the opposite end of the strip and form a band. The strip is also provided with markings, as indicated at 5, on which it may be shortened by cutting.

A clasp 7 comprises a flat, flexible, elastic strip shaped to form a body having an integral tongue 9 on one end and in the same plane therewith. A headed stud 6 is attached to said body near its other end. The stud 6 is preferably made of metal or other rigid material and has a base embedded in the body part of the clasp from which the headed stud projects. The tongued end of the clasp is provided with an eye 10 of smaller

diameter than the head of the stud 6, and the margins of this eye are of rubber so that it will yield when it engages or disengages the stud.

The tongue 9 is also provided with a metallic wire reinforcement 8 around its outer marginal edge which stiffens the tongue to facilitate manipulating it but leaves the inner margin of the eye free to yield when it engages and disengages with the stud 6.

In operation, the stud of the clasp is inserted through one of the perforations 3 in the strip, and from the inner face of the garter strip 1 so that the head of the stud projects outward through the strip. A hem of a garment is placed over the strip 1 and the tongued end of the clasp is bent over the outer face of the strip and over the garment; then the eye 10 is sprung over the head on the stud, thereby holding the garment on the garter. Any number of clasps may be used in connection with this type of garter, as may be necessary or desirable.

Although but one specific embodiment of this invention has been herein shown and described, it will be understood that certain details of the construction shown may be altered or omitted without departing from the spirit of this invention as defined by the following claims:

1. A clasp comprising a flat flexible strip shaped to form a body with an integral tongue at one end and in the same plane therewith, and a headed stud attached to said body and adjacent the end opposite said tongue, said tongue being provided with an eye of smaller diameter than the head of said stud and having an elastic margin for engagement therewith, and said tongue having a stiff reinforcement around its outer marginal edges and spaced away from said eye so that the margin of said eye will yield when it engages and disengages said stud.

2. A clasp comprising a flat flexible strip shaped to form a body with an integral tongue at one end and in the same plane therewith, and a headed stud attached to said body and adjacent the end opposite said tongue, said tongue being provided with an eye of smaller diameter than the head of said stud and hav-

ing an elastic margin for engagement therewith, and said tongue having a wire reinforcement around its outer marginal edges and spaced away from said eye so that the margin of said eye will yield when it engages
5 and disengages said stud.

JOSÉ MIERES.
